US00D589810S

(12) **United States Design Patent**
van der Krog et al.

(10) **Patent No.:** **US D589,810 S**
(45) **Date of Patent:** **** Apr. 7, 2009**

(54) **CONTAINER AND CLOSURE**

(75) Inventors: **Pepijn Rutger van der Krog**, Santiago (CL); **Fernando Muniz-Simas Moreira**, Santiago (CL); **Robert Monaghan**, London (GB); **Bruce Cummings**, New York, NY (US); **Guillermo Weyland**, Santiago (CL)

(73) Assignee: **Colgate-Palmolive Company**, New York, NY (US)

(**) Term: **14 Years**

(21) Appl. No.: **29/281,596**

(22) Filed: **Jun. 27, 2007**

(51) LOC (9) Cl. **09-01**

(52) U.S. Cl. **D9/529**; D9/549; D9/552; D9/565; D9/435

(58) **Field of Classification Search** D9/516, D9/529, 537-543, 549, 551, 552, 556, 557, D9/558, 559, 564, 565, 569, 570, 571, 574, D9/575, 434, 435; 215/381-385

See application file for complete search history.

(57) **CLAIM**

The ornamental design for a container and closure, as shown and described.

DESCRIPTION

FIG. 1 is a perspective view of the container and closure of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view of the container and closure of FIG. 1 with a change in the density of stippling of the container to denote a gradation of the container color or texture from a lower portion to an upper portion.

FIG. 9 is a front elevation view thereof.

FIG. 10 is rear side elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The broken line showing of part of the bottom portion of the container is for illustrative purposes only and forms no part of the claimed design.

1 Claim, 12 Drawing Sheets
